Patented Jan. 31, 1922.

UNITED STATES PATENT OFFICE.

ARTHUR C. VAN KIRK, OF MIDDLETON, OHIO, ASSIGNOR OF ONE-HALF TO HORACE M. POTTER, OF CINCINNATI, OHIO.

VACUUM SYSTEM.

1,405,363.

Specification of Letters Patent. Patented Jan. 31, 1922.

Application filed March 25, 1920. Serial No. 368,776.

To all whom it may concern:

Be it known that I, ARTHUR C. VAN KIRK, a citizen of the United States, residing at Middleton, in the county of Butler and State 5 of Ohio, have invented a new and useful Vacuum System, of which the following is a specification.

This invention relates to new and useful improvements in internal combustion engines, and it is the primary object of the invention to provide means adapted to be attached to the crank case of the engine, for automatically sucking the unburned gases, which ordinarily collect in the crank 10 casing, into the cylinders of the engine where the same mixes with the incoming gases, thus reducing the consumption of fuel to a minimum.

A further object of the invention is to 20 provide a device of this character which may be readily attached through the filling opening of the crank casing, and one which will collect the unburned gases, thus eliminating the possibility of the lubricating oil in 25 the crank case being thinned by gas leaking past the pistons.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 35 within the scope of what is claimed, without departing from the spirit of the invention.

Referring to the drawing:—

Figure 1 illustrates a side elevational view 40 of an internal combustion engine showing the device as applied.

Figure 2 illustrates a sectional view taken on line 2—2 of Figure 1.

Referring to the drawing in detail, the 45 reference character 5 designates a relatively long pipe having a lower threaded extremity by means of which the same may be positioned in the usual threaded filling opening of a crank casing.

50 The upper extremity of this pipe 5, is provided with a relief valve 6 of any suitable construction to permit the passage of air from the crank case, thus insuring against an accumulation of pressure within 55 the crank case.

A relatively small pipe 7, provides com-

munication between the pipe 5 and the manifold of the engine, the pipe having connection with the pipe 5 adjacent the upper end thereof, so that the direct suction of the 60 pistons will not effect the oil within the crank casing, but on the other hand act to draw the unburned gases which usually collect in the crank, therefrom.

The opposite end of the pipe 7 has connection with the manifold of the engine indicated at 8, and this connection includes a rotating valve indicated at 9 adapted to be actuated by the rod 10, having one end thereof connected to the valve 9, as at 11, the opposite end of the rod 10 having connection with an operating lever 12 pivotally supported on the steering column 13, and disposed at a point adjacent to the steering 70 wheel 14.

In the operation of the device, the pistons operating in the cylinders of the engine create a suction through the manifold 8, the unburned gases being drawn through the pipe 5 and pipe 7, where the same mix 80 with the incoming gas passing through the manifold with the result that the gases are preheated, and the quantity of fluid consumption reduced to a minimum.

If it is desired to throw the attachment 85 out of operation, it is only necessary to actuate the lever 12 to close the pipe 7, thereby cutting off the supply of gases to the manifold.

Having thus described the invention, what 90 is claimed as new is:—

In a device of the character described, a pipe having a threaded extremity adapted to be positioned within the threaded opening of a crank casing, a relief valve positioned 95 in the upper end of the pipe, a relatively small pipe in communication with the first mentioned pipe at a point in spaced relation with the manifold of an engine, a control valve said relatively small pipe having 100 communication with the control valve, and said control valve adapted to be operated to cause a suction to be created through the pipes and the crank casing.

In testimony that I claim the foregoing 105 as my own, I have hereto affixed my signature in the presence of two witnesses.

ARTHUR C. VAN KIRK.
